(74) Attorney, Agent, or Firm — McHale & Slavin, P.A.

(57) **CLAIM**

The ornamental design for a wall mounted vacuum cleaner, as shown and described.

DESCRIPTION

FIG. 1 is a perspective view of a wall mounted vacuum cleaner showing my new design;

FIG. 2 is a front view thereof;

FIG. 3 is a top view thereof;

FIG. 4 is a bottom view thereof;

FIG. 5 is a rear view thereof;

FIG. 6 is a left side view thereof;

FIG. 7 is a right side perspective view thereof; and,

FIG. 8 is a perspective view thereof mounted between two wall studs.

The portions of the wall mounted vacuum cleaner illustrated in broken lines form no part of the claimed subject matter.

1 Claim, 8 Drawing Sheets(56)
